UNITED STATES PATENT OFFICE.

ELLSWORTH B. A. ZWOYER, OF PERTH AMBOY, NEW JERSEY, ASSIGNOR TO THE GENERAL FUEL BRIQUETTE CORPORATION, OF NEW YORK, N. Y., A CORPORATION OF NEW YORK.

BRIQUETTING METHOD.

Application filed April 8, 1925. Serial No. 21,476.

This invention relates to roller presses of the type employed for the agglomeration or briquetting of loose materials capable of being compressed or compacted into briquettes. 5 Briquetting presses as heretofore constructed are of two general types known as mechanical feed and gravity feed presses. The former is characterized by the provision of preliminary mechanically operated feeding devices which force the material to the bight of the briquetting rolls and while such presses give fairly satisfactory results, they are subject to the objection that the pressure placed on the material can not be regulated. 10 The gravity feed type is characterized by the omission of preliminary mechanically operated feeding devices, the material being fed to the bight of the rolls from a vertically extending column of material placed in a suitable hopper located above the rolls and so arranged that the column is supported by the roll surfaces. With this arrangement, the material is pressed or forced directly into the bight of the rolls by the pressure 15 due to the weight of the column, which pressure obviously can be varied by regulating the height of the column.

The present invention relates more particularly to the gravity feed type of briquetting presses, which although they have the advantage of enabling the briquetting pressure to be varied between wide limits, exhibit the peculiarity which I have discovered, that while rolls of a given size or diameter will give entirely satisfactory results for a certain material, such rolls will not work satisfactorily for other materials and in some instances will even fail entirely to produce a compacting or coherence of such other materials. After many experiments, I have also discovered that the failure of a given press having rolls of a given or certain diameter to compact certain materials is caused by differences in the specific gravity 5 of the material treated. Further experiments have proven that if a certain definite relationship be maintained between the roll diameters of the press rolls and the specific gravity of the material being treated, a successful briquetting action can be obtained of any loose material capable of being briquetted.

In order to overcome the objection due to the above noted peculiarity, one of the principal objects of this invention is to provide

a briquetting press in which the diameters of the press rolls bear a certain definite, predetermined relation to the specific gravity of the material being treated. Another object is to provide a method for determining or 60 proportioning the roll diameters of a briquetting press according to, or in a certain definite predetermined relationship with, the specific gravity of the material to be treated.

In the accompanying drawings forming a part hereof, Fig. 1 is a side elevation of a briquetting press of the type to which this invention relates and Fig. 2 is a graph or chart which indicates the nature of the relationship between the roll diameters and material.

The press shown in Fig. 1 comprises a pair of cylindrical rolls *a* and *b*, having the circumference thereof provided with a plurality of similar, equally spaced recesses *c*, of 75 equal dimensions. An equal number of these recesses are provided on each roll and the gears *d* are fixed upon shafts *e* upon which the rolls are secured. The gears *e* are constructed and arranged to intermesh with a gear train *f* to cause the recesses of one roll to register or align in cooperating relationship with the recesses of the other roll to form pockets in which the briquettes 80 are formed. Power from any suitable source may be supplied for rotating the press rolls.

In the graph shown in Fig. 2, the ordinates represent different values of the specific gravity of the material to be treated 90 while the abscissa represent the sizes of the roll diameters. The relationship which I have discovered must exist between the specific gravity and the roll diameter, is represented by the curve A, B, which curve corresponds substantially to the equation $(x-h)^2 + (y-k)^2 = a^2$ where *x* equals the roll diameter, *y* equals the specific gravity, and *h*, *k*, and *a* are constants. The value of the constants depends upon the length of the 95 briquette along the roll circumference. Assuming a briquette having a dimension or length of two inches along the roll circumference and by taking the ordinates for the specific gravity ten fold, in order to avoid 100 fractions, the values of such constants for the curve drawn to the scale shown are *h*=36.25, *a*=26.25, and *a*=21.25.

An application of the method for determining the required roll diameter for a 110

given material, is as follows: Assuming that the material to be treated is magnetic flue dust having a specific gravity of 1.6, by taking the abscissa of the curve AB corresponding to the ordinate 16 or ten times 1.6, the value of such abscissa will be found to be 17, therefore a roll having a diameter of 17" should be used.

The curve AB shown in Fig. 2 represents the proper values and relationships for briquettes 2 inches long along the circumference of the press rolls. If this dimension of the briquette is varied or departed from, it then becomes necessary to modify the roll diameter determined above. The required modification can be readily determined by reference to the equation $D = \frac{dl}{2}$ where d equals the diameter of the roll as determined from the graph or curve and l equals the length of the new briquette.

The relationship between the specific gravities and roll diameters given by the equation holds true for all values of the specific gravities between the limits ($k-a$) or 5 and k or 26.25 respectively, while for values below or above such limits the curve approaches a straight line which is parallel to the X axis for the case of the lower limits and parallel to the Y axis for the upper limits.

I claim:

1. In the art of briquetting by the use of presses of the gravity feed type, the method which consists in first determining the specific gravity of the material to be briquetted, then computing the diameter of the rolls of the press to be employed for briquetting such material, by reference to a formula typified by a graph, the characteristics of which are substantially expressed by the equation $(x-h)^2 + (y-k)^2 = a^2$ where x equals the roll diameter, y , the specific gravity of the material to be treated, and h , k , and a are constants whose values are respectively equal, for ordinates of ten times the specific gravity, to 36.25, 26.25, and 21.25 for briquettes having a length of two inches along the circumference of the roll, then incorporating in the press a roll having a thus determined diameter and subjecting material of the said specific gravity to the action of said rolls.

2. In the art of briquetting by the use of presses of the gravity feed type, the method which consists in first determining the specific gravity of the material to be briquetted, then computing the diameter of the rolls of the press to be employed for briquetting such material by reference to a formula typified by a graph, the characteristics of which are substantially expressed by the equation $(x-h)^2 + (y-k)^2 = a^2$ where x equals the roll diameter, y , the specific gravity of the material to be treated, and h , k , and a are

constants whose values are respectively equal for ordinates of ten times the specific gravity to 36.25, 26.25, and 21.25 for briquettes having a length of two inches along the circumference of the roll, modifying the value for said roll diameter obtained from said graph for briquettes of different dimensions

by reference to the equation $D = \frac{dl}{2}$ where d equals the value obtained from said curve, and l equals the dimension of the briquette, incorporating in the press a roll having a thus determined diameter and subjecting material of the said specific gravity to the action of said rolls.

3. In the art of briquetting by the use of presses of the gravity feed type, the method which consists in first determining the specific gravity of the material to be briquetted, then computing the diameter of the rolls of the press, to be employed for briquetting such material, by reference to a formula typified by a graph, the characteristics of which are substantially expressed by the equation.

$$(x-36.25)^2 + (y-26.25)^2 = 21.25^2$$

where x equals the roll diameter, and y the specific gravity of the material to be treated, then incorporating in the press a roll having a thus determined diameter and subjecting material of the said specific gravity to the action of said rolls.

4. In the art of briquetting by the use of presses of the gravity feed type, the method which consists in first determining the specific gravity of the material to be briquetted, then computing the diameter of the roll of the press to be employed for briquetting such material, by reference to a formula typified by a graph whose characteristics are expressed by the equation

$$(x-h)^2 + (y-k)^2 = a^2$$

where x equals the roll diameter, y the specific gravity of the material to be treated, and h , k , and a are constants, incorporating in the press a roll having a thus determined diameter and subjecting material of the said specific gravity to the action of said rolls.

5. In the art of briquetting by the use of presses of the gravity feed type, the method which consists in first determining the specific gravity of the material to be briquetted, then computing the diameter of the rolls of the press to be employed for briquetting such material by reference to a formula typified by a graph having a definite curvature and representing definite predetermined relationships between various specific gravities and roll diameters, incorporating in the press a roll having a thus determined diameter and subjecting material of the said specific gravity to the action of said rolls.

ELLSWORTH B. A. ZWOYER.
